(57) CLAIM

The ornamental design for a shoulder injury prevention device, as shown and described.

DESCRIPTION

FIG. 1 is a perspective view of a left side component of a shoulder injury prevention device showing our new design. FIG. 2 is a right side view thereof.

FIG. 3 is a left side view thereof.

FIG. 4 is a rear side view thereof.

FIG. 5 is a front side view thereof.

FIG. 6 is a top view thereof.

FIG. 7 is a bottom view thereof.

FIG. 8 is a perspective view of a right side component of the shoulder injury prevention device showing our new design.

FIG. 9 is a right side view thereof.

FIG. 10 is a left side view thereof.

FIG. 11 is a rear side view thereof.

FIG. 12 is a front side view thereof.

FIG. 13 is a top view thereof.

FIG. 14 is a bottom view thereof.

FIG. 15 is an exploded front perspective view showing an environment utilizing our a shoulder injury prevention device.

FIG. 16 is a front perspective view showing the shoulder injury prevention device installed in the environment shown in FIG. 15.

FIG. 17 is a front perspective view showing the shoulder injury prevention device installed in the environment shown in FIG. 15 and in use; and,

FIG. 18 is a rear perspective view showing the shoulder injury prevention device installed in the environment shown in FIG. 15 and in use.

The broken lines in the drawings depict features that form no part of the claimed design.
